DRYING SYSTEM AND METHOD

David D. Peebles, Eureka, Calif.

Application September 24, 1932, Serial No. 634,738

3 Claims. (Cl. 34—24)

This invention relates generally to systems and methods for the drying of various materials, particularly materials which in the past have been dried upon heated drums.

5 In the past many industrial processes have made use of drum type dryers for recovering solid components of fluid material in dry form. Such dryers commonly utilize a steam heated drum upon the outer surface of which a layer of the fluid material is applied. In operation, I have found that such dryers are characterized by fairly efficient evaporation of moisture, until the material contains in the neighborhood of say 40 to 60% solids, after which the drying action is 10 increasingly less efficient. This is due to the fact that it is more difficult to drive off moisture from the denser material, because ebullition is retarded and heat conductivity is reduced. In view of this characteristic if it is desired to carry 15 the moisture content down to say one or two percent, drum type dryers become relatively inefficient, and if a considerable plant capacity is desired, a large number of such dryers must be employed at great expense.

20 25 It is an object of the present invention to devise a drying system and method which will make use of a drum type dryer only to the extent to which such dryers are relatively efficient, and which will finish the drying of the material in an efficient and simple manner.

30 35 A further object of the invention is to provide a system and method of the above character which will materially reduce the time required for drying materials in plant operations, which will have relatively high capacity compared to its size, and which will result in a relatively uniformly dried product.

40 45 Further objects of the invention will appear from the following description in which the preferred embodiment of my invention has been set forth in conjunction with the accompanying drawing. It will be understood that the appended claims are to be accorded a range of equivalents consistent with the state of the prior art.

50 55 My system as diagrammatically illustrated in the drawing consists of a drum type dryer 10, in conjunction with a finishing dryer 11. An amount of drying is carried out by the drum type dryer 10 consistent with the range for which this dryer is relatively efficient and to an extent which will enable removal of the material, while the remainder of the drying, down to say 1 to 2% of moisture, is accomplished in the finishing dryer 11. The extent of drying in the drum type

dryer will obviously depend somewhat upon the character of the material being treated.

The drum type dryer 10 consists of a rotatable drum 12, adapted to be heated by steam. The supply of material in fluid condition to be dried is indicated at 13, and this material is spread upon the heated periphery of the drum 12, by applicator 14. A knife edge, brush or other scraping means is indicated at 16, for removing the semi-dried material from the drum, and for delivering it into suitable conveying means 17.

The finishing dryer 11 consists of a chamber 18, which can be cylindrical in shape, and which is provided with inflow and outflow conduits 19 and 21. Movements of gas thru chamber 18 is 15 maintained by connecting outflow conduit 21, to the inlet of a blower 22, the discharge conduit 23 of which may lead to further apparatus, as for example a bag filter. The drying gas flowing in thru conduit 19, which may be air, is heated to a 20 suitable elevated temperature by suitable means such as a heater 24. Conveyor 17 is arranged to deliver the semi-dried material into conduit 19, 25 thru the conduit connection 26, so that this material is conveyed by the rapidly moving stream 25 of air and delivered into the chamber 18 for further treatment. It will be noted that the connection between conduit 19 and chamber 18 is arranged tangentially, to aid in causing currents of air within the treatment chamber 18 to swirl 30 about a central axis.

In order to maintain a sufficient period of contact between the material being dried and the drying gas, I preferably provide recirculation means in conjunction with chamber 18. This 35 recirculation means can consist of a blower 27, having its inflow conduit 28 connected tangentially to chamber 18, and having a similar tangential connection for its outflow conduit 29. The tangential connection between blower 27 and the treatment chamber further aids in maintaining swirling currents of drying gas in which the material is suspended. If desired the flow 40 of air can be maintained by a blower interposed in conduit 19, in place of or supplemental to 45 blower 22.

Outflow conduit 21 connects with chamber 18 thru the upper wall of this chamber, and in substantial alinement with the vertical axis of the swirling currents of gas. Since the temperature of gas leaving thru conduit 21 may at times be sufficiently high to burn a bag type filter, I 50 preferably provide suitable cooling means such as a conduit or pipe 31, by means of which regulated quantities of cool air can be introduced into 55

conduit 21. Valve 32 in conduit 31 can be controlled automatically in accordance with the temperature of gas flowing thru conduit 21. Thus I have shown as electrical circuit 33, including a solenoid actuator 34 and an electrical thermostat 36 associated with conduit 21. In the event the temperature of gas flowing thru conduit 21 becomes too high, which may be due to an abnormal decrease in the flow of material to dryer 11, valve 32 will be automatically opened to admit cool air.

Operation of my system and method will be described with respect to the drying of magnesium basic carbonate, because my invention affords a practical and novel solution of the problem of drying this material as produced in industrial processes. The fluid material, consisting in this case of a suspension of magnesium basic carbonate in water, is supplied to the drum dryer 10 at 13. As the material is delivered from the drum dryer to the conveyor 17, it contains in the neighborhood of from 50 to 60% or more solids. Such material is sufficiently dry that it can be conveyed pneumatically thru conduit 19, and will be suspended by the swirling currents of drying gas in chamber 18 without atomization. In chamber 18 the material is maintained in suspension in contact with the drying gas or hot air, until the moisture content has been reduced to from say 1 to 2%, after which the dried particles are carried pneumatically thru conduit 21 and delivered to conduit 23. Within chamber 18 the material is not only contacted with the drying gas, but there is also an automatic classifying action. Particles which are not sufficiently dried for delivery thru conduit 21, tend to remain within this chamber, and also tend to progress downwardly and to be redelivered by blower 27 to the upper portion of the chamber. Thus all particles of the basic carbonate are subjected to the drying gas for a sufficiently long period until the moisture content has been reduced to the desired value, after which they are delivered to conduit 21.

It is evident that my system and method has many desirable characteristics. The drum type dryer is utilized only for an efficient range of operation, thus making possible relatively high plant capacity with comparatively few dryers of this type. For example it has been found that two drum type dryers, utilized in my system, will handle substantially the same capacity as five or more drum type dryers utilized as in the past in such a manner as to complete the drying of the material. My finishing dryer 11 is relatively inexpensive and simple to operate, compared to the additional drum type dryers which

would be required to complete the drying, if my system were not employed. Likewise because of the use of my finishing dryer in conjunction with a drum type dryer, I need only utilize sufficient air to maintain the particles of material in the treatment chamber 18 in suspension, and special rotary atomizers need not be employed.

I claim:

1. In a drying system, a desiccating chamber, means for introducing a stream of drying gas tangentially into said chamber, means for entraining divided material to be desiccated into said stream of gas prior to introducing the gas into the chamber, means including an external blower forming a recirculation path for continuously removing a portion of the gas and entrained material from the lower portion of said chamber and for re-introducing the same back into the upper portion of the chamber, and means for continuously removing gas together with entrained and desiccated material from said chamber, said last means including an outflow conduit having an open inlet end located near the upper end of the central axis of the desiccating chamber.

2. In a drying system, a desiccating chamber, means for introducing a stream of drying gas tangentially into said chamber, means for entraining divided material to be desiccated into said stream of gas prior to introducing the gas into the chamber, means including an external blower forming a recirculation path for continuously removing a portion of the gas and entrained material from the lower portion of the chamber and for introducing the same back into the upper portion of the chamber in a tangential direction, and means for continuously removing gas together with entrained and desiccated material from the upper portion of said chamber, said last means including an outflow conduit having an open inlet end located near the central axis of the chamber.

3. In a drying method characterized by the use of a desiccating chamber, introducing a stream of drying gas tangentially into said chamber, feeding divided material to be desiccated into said stream of gas and conveying the material by the stream of gas into the chamber, continuously diverting a stream of gas from one end portion of the chamber, adding kinetic energy to the gas so diverted and returning the same back into the other end portion of the chamber, and continuously removing gas together with entrained and desiccated material from a localized region near the central axis of the chamber and in a generally upward direction.

DAVID D. PEEBLES.
